UNITED STATES PATENT OFFICE.

ERWIN W. SECKLEMAN, OF CHICAGO, ILLINOIS.

IRONING-BOARD.

1,324,931.

Specification of Letters Patent.

Patented Dec. 16, 1919.

Application filed June 9, 1919. Serial No. 302,681.

To all whom it may concern:

Be it known that I, ERWIN W. SECKLEMAN, a citizen of the United States, residing at Chicago, in the county of Cook and State 5 of Illinois, have invented certain new and useful Improvements in Ironing-Boards, of which the following, when taken in connection with the drawing accompanying and forming a part hereof, is a full and complete 10 specification.

This invention relates to ironing boards which are designed and adapted to be attached to kitchen and other tables, to enable the person using the same to iron skirts and 15 like articles thereon with less difficulty than on an ordinary table.

Among the objects of this invention are to obtain an ironing board of the character named which may be adjusted to present a 20 substantially level, (or horizontal) surface when attached to tables of different heights; which may be attached to tables of different thickness and present a level surface; which will grasp, or hold to, a table firmly, without 25 scarring or marring the same; and which will present a safe and convenient resting place for a hot flat iron.

Additional objects are to obtain an ironing board which is simple in construction; 30 easily attached and detached from an ordinary table or shelf; and easily adjusted.

A construction embodying this invention is illustrated in the drawing referred to, in which,

35 Figure 1, is a top plan view of the ironing board and a portion of the top of a table to which it is attached.

Fig. 2 is a side elevation of the board illustrated in Fig. 1, and of the table to 40 which it is attached;

Fig. 3 is a bottom plan view of one of the members of the construction illustrated in Figs. 1 and 2; and

45 Fig. 4 is a side elevation of one end of the ironing board, detached from the table which is illustrated in Figs. 1 and 2, with the several elements thereof in a folded condition.

A reference letter applied to designate a 50 given part indicates said part throughout the several figures of the drawing, wherever the same appears.

A represents a portion of the top of an ordinary kitchen table; and B a leg thereof. 55 C represents the board of the ironing table on the surface of which articles are ironed.

The ordinary cloth covering is laid on this board, but of course forms no part of the invention, and is not illustrated. D is a jaw which is represented as rigidly secured to 60 the underside of board C, by screws d, d. E represents an additional jaw, which is adapted to co-act with jaw D, to attach the board to table A; and is pivotally attached to said jaw D by bolt or pin e. F represents 65 a brace or strut to which the jaw E is adjustably attached, by means of pin f, threaded bolt G and nut H. Bolt G is represented as pivotally attached to brace or strut F, by pin or bolt g. Nut H is represented as having groove h thereto, around the body part thereof, and with the knurled peripheral part h¹, by means of which it may be easily turned on said bolt F.

The jaws D and E are represented of sheet 75 metal, with a body part d¹, and e¹, respectively, and with the upturned edges d², e². And the jaw E is provided with the aperture I¹, of two diameters, the part I thereof, (of larger diameter) being slightly larger 80 than the diameter of annular portion H¹ of nut H, and the part i thereof of substantially the same size as the diameter of the bottom of groove h in said nut.

To set up the ironing board the nut H is 35 partially entered in aperture I¹ and brace or strut F is turned on pin f so that said nut H may be moved, (bolt G turning on pin or pivot g) until said nut is in the smaller portion (i) of said aperture that is with the 90 edges of said smaller portion in groove h.

The jaws D, E, are then placed on the table and as board C is lowered toward a horizontal position said jaws will automatically grasp the top A, of the table. The nut 95 H is then turned on bolt G until said board C is in a substantially horizontal position. By holding the end of the table C up, so that said table is substantially horizontal, the adjustment of said nut H is more easily 100 made.

The up-turned edges e² of that portion of jaw E which are above the table, and in a substantially horizontal plane, form a rest on which a flat iron may be placed, and X, 105 Fig. 2 represents a flat iron resting on said up-turned edges.

I claim:

1. In an ironing board, a table, a jaw rigidly secured to said table, and an additional 110 jaw pivotally attached to said first named jaw, said additional jaw comprising a body

part adapted to rest on a table and up-turned edges adapted to form a flat iron rest, in combination with a diagonally extending member, and adjustable means to attach said 5 additional jaw to said member.

2. In an ironing board, a table, a jaw rigidly secured to said table, and an additional jaw pivotally attached to said first named jaw, in combination with a diagonally extending member, a threaded bolt, a nut, 10 means to pivotally attach said additional

jaw and said bolt respectively, to said last named member, and said jaw provided with a key hole slot, the larger end thereof admitting said nut thereto, and said nut provided with an annular groove, fitting in the other end thereof. 15

ERWIN W. SECKLEMAN.

In the presence of—

CHARLES TURNER BROWN,
GERTRUDE SECKELMAN.
